UNITED STATES PATENT OFFICE.

CHARLES G. NELSON, OF CHICAGO HEIGHTS, ILLINOIS, ASSIGNOR TO ZOURI DRAWN METALS COMPANY, OF CHICAGO HEIGHTS, ILLINOIS, A CORPORATION OF ILLINOIS.

METAL WINDOW-PANE HOLDER.

Application filed March 25, 1926. Serial No. 97,262.

My invention relates to a holder for window panes and has for its purpose to provide such a holder which may be readily and accurately applied and which will retain the several parts in proper relation to each other. The specific improvements and objects of my invention will appear as the description proceeds.

In the accompanying drawing forming a part of this specification, Figure 1 is a section through a portion of a pane fastener embodying my invention; Fig. 2 is a plan view of the clamping bracket; Fig. 3 is a front view of the same; Fig. 4 is a section on the line 4—4 of Fig. 1, and Fig. 5 is a partial section similar to Fig. 1, but showing a different form of front clamping member or face plate.

For convenience, the device will be described as applied on the window sill, at the bottom of a pane of glass, but it will be readily understood that it may be used at the sides or top of a pane of glass or anywhere where such a fastening device is described.

In Fig. 1 there is shown a sill 10 beneath the bottom of a window pane 11. The pane is supported at a short distance above the sill by suitable supporting blocks, not shown. A rear clamping plate 12 has a forwardly extending flange 13 at its upper side with a downwardly bent portion 14 adapted to rest against the rear side of the glass. A flange 15 projects from the lower edge of plate 12 and rests on sill 10.

A bracket member 16 has upright portion 17 adapted to fit against the upright portion of member 12 and within the channel at the upper edge of member 12. Extending from the bottom of portion 17 there is a horizontal portion 18 which rests upon flange member 15. The forward end of portion 18 is raised at 19. In the construction shown, there are stiffening side flanges 20 at each side of this bracket member.

A front clamping member or face plate 21 is provided having an upper flange 22 adapted to rest against the front of the pane of glass and having a lower flange 23 extended inward from the point 24 where the member rests upon the sill, flange 23 being raised a slight distance above the sill. As will be seen, the flange 23 fits between the front end 19 of the above described bracket member and flange member 15.

A fastening lug 25 is positioned above portion 18 of bracket 16. Portion 18 of bracket 16 has a hole therethrough, and a portion of lug 25 is punched through this hole and rivets the lug to the bracket, as shown at 26. The lug has a substantially vertical portion 27 in which there is a threaded opening 28. A screw 29 passes through a hole 30 in the face plate and is threaded into hole 28 in the lug and holds the face plate in proper position.

In the construction shown, the rear clamping plate has an offset portion 31 which connects the vertical portion with flange 15, and bracket 16 is formed with a notch at 32 which fits over portion 31 and holds member 12 in place. Member 12 is first placed in the sill, with brackets 16 in place. Then a screw 33 is driven through aligning holes in lug 25, bracket 16 and flange 15 and into sill 10, securing on the sill the parts mentioned. Thereafter window pane 11 is mounted in position in blocks, not shown, which rest upon flange 15 between brackets 16. Then member 21 is placed in position, and the assembly is completed by inserting screws 29.

End 19 of flange 18 is preferably raised above flange 15 more than the thickness of the metal of front clamping plate 21, and offsets 34, 34 are bent upward in the edge of flange 23, these offsets fitting snugly beneath end 19 when the bottom of flange 23 rests on flange 15. This structure is shown most clearly in Fig. 4.

In Fig. 5 there is shown an alternative form of face plate 21a. The portions of this face plate corresponding to the face plate shown in Fig. 1 are designated by similar reference numerals with the addition of the letter "a." The portion 19a of the bracket, shown in Fig. 5, is slightly modified, and it will be readily understood that other obvious changes may be made in the details of the structure.

The face is made of resilient metal, and flange 23 may be bent upward to such an extent that it is somewhat depressed by bracket portions 19. In this way the face plate may be held resiliently against the glass as soon as it is slipped into place, and screws 29 may be employed merely to hold the face plate in the position which it assumes when shoved into place.

It will be seen from the above that I have

provided a holding device for glass panes which may be readily and accurately affixed in proper relation to the pane and to the surrounding frame. I have shown one possible variation of the form of the face plate and it will be readily understood that various other modifications of the exact structure disclosed may be made within the terms of the appended claims which define my invention.

I claim:

1. In a support for a window pane, a supporting member beyond one edge of the pane and approximately perpendicular to the plane of the pane, a clamping member having one edge adapted to rest against the pane, having a bead along its other edge adapted to rest against said supporting member, and having a flange adjacent the bead adapted to extend towards the plane of the pane and spaced away from said supporting member, and a fastening member attached to said supporting member and having a flange overlying the said flange of the clamping member.

2. In a support for a window pane, a supporting member beyond one edge of the pane and approximately perpendicular to the plane, the clamping member having one edge adapted to rest against the plane of the pane, having a bead along its other edge adapted to rest against said supporting member, and having a flange adjacent the bead adapted to extend towards the plane of the pane and spaced away from said supporting member, a fastening member attached to said supporting member and having a flange overlying the said flange of the clamping member, a fastening lug attached to said supporting member, and adjustable means adapted to secure said clamping member to said lug.

3. In a support for a window pane, a supporting member beyond one edge of the pane and approximately perpendicular to the plane of the pane, an inner clamping member and an outer clamping member, each having a flange along one edge adapted to contact with a face of the pane and having a flange along the other edge adjacent the supporting member, an attaching bracket secured to said supporting member, having one end adapted to interlock with said inner clamping member, and having a part adapted to overlie the flange of said outer clamping member which is adjacent the supporting member, an attaching lug secured to said supporting member and to the overlying portion of said bracket, between said supporting member and the edge of the glass, and adjustable means connecting said outer clamping member to said lug.

4. In a support for a window pane, a supporting member beyond one edge of the pane and approximately perpendicular to the

plane of the pane, an inner clamping member and an outer clamping member, each having a flange along one edge adapted to contact with a face of the pane and having a flange along the other edge adjacent the supporting member, one of said last mentioned flanges overlying the other, an attaching member overlying the last mentioned flanges of both the inner and outer clamping members, a lug adjacent the inner face of the overlying portion of said attaching member and secured therewith to the supporting member, and means for securing the inner clamping member directly to said lug.

5. In a support for a window pane, a supporting member beyond one edge of the pane and approximately perpendicular to the plane of the pane, an inner clamping member and an outer clamping member, each having a flange along one edge adapted to contact with a face of the pane and having a flange along the other edge adjacent the supporting member, and a stiffening bracket within said inner member and having a forwardly extending flange secured to the supporting member and overlying the adjacent flange of the outer member, one of said two last mentioned flanges having offset notches bearing against the other of said two flanges.

6. In a support for a window pane, a supporting member beyond one edge of the pane and approximately perpendicular to the plane of the pane, an inner clamping member and an outer clamping member, each having a flange along one edge adapted to contact with a face of the pane and having a flange along the other edge adjacent the supporting member, and a stiffening bracket within said inner member and having a forwardly extending flange secured to the supporting member and overlying the adjacent flange of the outer member, a lug secured to the overlying portion of the flange of the stiffening bracket, said lug being formed with an angularly extending reinforced portion between the flange of the stiffening bracket and the edge of the glass and adjustable means securing the outer clamping member to the reinforced portion of the lug.

7. In a support for a window pane, a supporting member beyond one edge of the pane and approximately perpendicular to the plane of the pane, an inner clamping member and an outer clamping member, each having a flange along one edge adapted to contact with a face of the pane and having a flange along the other edge adjacent the supporting member, the last said flange of the outer member overlying the corresponding flange of the inner member, a stiffening bracket within said inner member and having a flange extending over the last said

flange of the outer member, and means securing the flanges of the stiffening bracket and the inner member to the supporting member.

5. 8. In a support for a window pane, a supporting member beyond one edge of the pane and approximately perpendicular to the plane of the pane, an inner clamping member and an outer clamping member, each 10 having a flange along one edge adapted to contact with a face of the pane and having a flange along the other edge adjacent the supporting member, the last said flange of the outer member overlying the correspond-

ing flange of the inner member, a stiffening bracket within said inner member and having a flange extending over the last said flange of the outer member, and means securing the flanges of the stiffening bracket and the inner member to the supporting 20 member, the flange of the outer member having offset notches whereby it fits snugly between the flanges of the bracket and the inner member.

In testimony whereof I have hereunto 25 signed my name to this specification.

CHARLES G. NELSON.
